FURNACE FOR BURNING FUEL CONSISTING
OF COMBUSTIBLE AND INCOMBUSTIBLE
MATERIALS

John E. Greenawalt, Bronxville, N. Y.

Application February 26, 1938, Serial No. 192,680

20 Claims. (Cl. 110—7)

This invention relates to a furnace for burning the combustible portion of a fuel consisting of combustible and incombustible materials and to the recovery of the incombustible material in a molten state. To accomplish this, the temperature of combustion and that of the furnace itself must be maintained above the melting point of the incombustible component of the fuel undergoing combustion.

10 In carrying out this invention, the structure described in my copending application, Serial No. 51,587, filed November 26, 1935 is especially applicable. The improved construction therein described as applied to a novel furnace for accomplishing and attaining the results flowing from this present invention will be hereinafter described.

The invention will be described with reference to its successful application to the burning of 20 waste black liquor, a by-product obtained in the manufacture of paper pulp and the recovery of the soda compounds therefrom; but the invention is applicable to many other uses.

For instance, this invention is applicable to 25 the burning of powdered coal and recovering the incombustible ash in a molten condition and thereby eliminating completely the objectionable "fly ash" which is discharged into the atmosphere by most of the present methods of combustion of such fuel.

Another adaptation of this invention would be 30 in the smelting of ores, especially the ores containing a certain percentage of sulphides in which the combustion of the sulphur and the oxidation of the metals produce sufficient heat to maintain the furnace at a temperature where all the incombustible portion of the charge is maintained in a molten condition and whereby the volatilization loss of valuable metals is reduced to a minimum.

40 In the manufacture of paper pulp, only about 50% of the wood entering the process is cellulose, the valuable ingredient available for pulp, the remainder consists of 30% lignin, 16% carbohydrates, 3.3% rosin and fats; all of which are dissolved by chemical solution during the cooking process. The liquor resulting from the cooking process is known as waste "black liquor" and contains about 50% of the wood entering the 45 process, and that part of the wood having the highest fuel value. This black liquor is produced in large quantities, and in the alkaline processes contains all the valuable soda compounds necessary for carrying out the processes. As it comes 50 from the digesters, where the cooking process

is carried out, it contains about 16.4% solid matter and 83.6% water, and will test 11° Bé. at 60° F. This liquor is then subjected by evaporation to varying degrees of concentration before being submitted to the recovery process, that is the process of recovering the valuable soda compounds. In some instances the concentration is conducted to the point where the liquor will contain 70% solids and 30% of water. Obviously, the greater the degree of concentration, the greater 10 is the percentage of solids in the liquor and the less the percentage of water, and therefore, the combustibility of the liquor is greatly increased as the concentration is increased. In practice, however, many obstacles are encountered with high 15 concentration, due to the high temperature required to keep the mass liquid and the strong tendency to deposit carbon and carbon compounds upon the evaporating surfaces.

20 As far as known, two methods for treating this liquor are in use at the present time. In one, the liquor is fed into one end of a revolving cylinder having a fire box at the discharge end and in passing through this rotary furnace, the water is evaporated, the volatile hydrocarbons burned and the soda, mixed with a large percentage of carbon, called char, is discharged from the furnace and is known as "black ash". In the soda recovery process this black ash is subjected to a leaching process whereby the soda 25 is dissolved and the char discharged as a waste product. In the sulphate process, this black ash is discharged into a smelting furnace where the char is burned and the soda recovered in a molten condition. In the other method, the liquor is sprayed into a combustion chamber and the water evaporated and some of the hydrocarbons burned and a large quantity of char is deposited 30 on either the bottom of the furnace or on the side walls of the furnace from which it drops 35 to the bottom of the furnace. However, in either case, the resulting mixture of char and soda is then subjected to a distinct and separate step of smelting with an independent blast of air.

40 The herein described process of my invention 45 is the first instance where this black liquor is treated in one single step for the recovery of the soda and the reclamation of the heat value of the fuel; that is to say, it is the first time this liquor has been burned successfully and the soda recovered by initiating combustion and completely 50 finishing it and producing molten soda in a single definite and continuous step. The relatively large percentage of water present in this black liquor, the large amount of incombustible material con- 55

tained by it and its low calorific value has made the accomplishment of this impractical with the means and devices heretofore available.

The present invention includes:

- 5 1. A novel combustion chamber having a baffle wall against which the molten incombustible material of the fuel impinges and flows into a quiescent zone from whence the molten incombustible material runs into troughs in the floor of the combustion chamber.
- 10 2. The incombustible liquid is separated from a turbulent zone by collecting it in a non-turbulent zone.
- 15 3. The provision of a combustion chamber with troughs shielded against the turbulent flow of products of combustion for collecting the molten incombustible material and discharging it through a common discharge nozzle.
- 20 4. A separation chamber where the products of combustion still carrying some of the finely divided particles of molten incombustible material must pass through, the remaining molten incombustible material being made to separate out of the gaseous products of combustion and flow into collecting troughs from which the molten incombustible material is recovered.
- 25 5. Preferably the combustion takes place in a combustion chamber under pressure above atmospheric so that the products of combustion will flow more uniformly and thereby have them perform more satisfactorily in the recovery of the incombustible material. This pressure also forces some of the products of combustion to accompany the molten incombustible material as it flows through the troughs in the floors of the combustion chamber and separation chamber. This keeps the molten incombustible material heated so that it remains liquid until it is recovered from the furnace.
- 30 40 6. Finally, the invention includes other features to be hereinafter described and shown in the drawings of the embodiments. The invention will be pointed out in the claims.

I have shown in the accompanying drawings only such parts of the furnace with which this invention is more directly concerned. Actually the furnace consists of a combustion chamber, a separation chamber and the usual type of boiler. As the boiler contains no novel features and as most any type of boiler can be adapted for use with this invention, the drawings show only the combustion chamber and the separation chamber.

Referring to the drawings:

Fig. 1 is a longitudinal cross section through the combustion chamber and separation chamber of the furnace along the line 4—4 of Fig. 2.

Fig. 2 is a plan view of cross section 2—2—2 of Fig. 1 looking in the direction of the arrows showing in part the broken chrome blocks covering the floor of the furnace and in part where the broken chrome blocks have been removed to show more clearly the construction of the floor below it.

Fig. 3 is a view to an enlarged scale looking in the direction of the arrow designated by 3 in Fig. 1 showing the construction of the checker wall.

Fig. 4 is a longitudinal cross section to an enlarged scale along the line 4—4 of Fig. 2 and looking in the direction of the arrows showing more clearly the construction of the drainage space between the side walls and the checker wall and the drainage troughs in the floor of the combustion chamber.

Fig. 5 shows to an enlarged scale a vertical

section through the center line of the fuel burner and shows clearly the fans used for propelling the fuel and air into the combustion chamber and showing more of the details of the shaft upon which these fans are mounted.

Fig. 6 is a section along the line 6—6 of Fig. 5 looking in the direction of the arrows showing the construction of the upper fan blades which propel a layer of secondary air into the combustion chamber.

Fig. 7 is a cross section along the line 7—7 of Fig. 5 looking in the direction of the arrows showing the middle fan blades which propel the fuel and primary air in the form of whirling jets into the combustion chamber.

Fig. 8 is a view of the bottom of the lower fan along the lines 8—8—8—8 of Fig. 5 looking in the direction of the arrows and showing the construction of the fan blades used for propelling a layer of secondary air into the combustion chamber.

Fig. 9 is a sectional view along the line 9—9 of Fig. 1 looking in the direction of the arrows and showing more clearly the design of the arched flue connecting the combustion chamber with the separation chamber lying beyond the combustion chamber.

Fig. 10 is a cross sectional view along the line 10—10 of Fig. 1 looking in the direction of the arrows showing more clearly the construction of the open (chrome checker brick walls in the separation chamber.

Similar parts bear the same numerals in the various figures.

In the drawings and more particularly Fig. 1, the outer airtight furnace wall 1 encloses the furnace proper. The three superimposed fans for propelling the black liquor, primary and secondary air into the combustion chamber are shown at 2. They are shown more clearly in Figs. 5, 6, 7 and 8.

The combustion chamber 6 is lined with chrome bricks 7. These chrome bricks form the refractory material protecting the outer walls of the furnace. A connecting flue 8 connects the combustion chamber 6 with the separation chamber 9. The products of combustion leaving the combustion chamber 6 pass through the flue 8 into the separation chamber 9 where they flow through the walls of open checker brick work 32 and the broken chrome blocks 33 between the checker brick walls. After flowing through this separation chamber the hot products of combustion flow out of the separation chamber at 10 and pass into a boiler of known construction. The boiler is not shown in the drawings but can be of the ordinary type for producing steam, the exit end 10 of the separation chamber through which the hot products of combustion pass can be easily changed to correspond to the entrance opening of the boiler. In this boiler the heated products of combustion are used for producing steam.

A vertical shaft 3 is provided upon which three fans are mounted and which extends vertically upward to a coupling 4 for coupling the shaft 3 with the motor 5. The upper fan 14 and the middle fan 15 and the lower fan 16 are superimposed. Fans 15 and 16 are made in one piece 70 having a central web carrying the blades 19 of the lower fan and the blades 18 of the middle fan. The web has a hub for mounting the fans on shaft 3. Fan 14 has a separate web carrying blades 17 but this web is held in position by 75

means of a rabbet fit on top of the blades of fan 15 and held in position by bolts 24 shown in Figs. 6, 7 and 8.

In Figs. 6, 7 and 8 the blade construction of each of these fans is more clearly shown. In Fig. 7 fan 15 has blades 18. These blades are radial at their exit ends and have a considerable thickness at exit. As this fan propels fuel and primary air into the combustion chamber the primary air containing atomized fuel will leave the fan in the form of jets of rectilinear cross section whose horizontal sides are very much longer than its vertical sides. The atomized fuel therefore presents a large surface to the adjacent secondary air propelled by fans 14 and 16. Figs. 6 and 8 show the construction of the blades of the upper fan 14 and the lower fan 16 respectively. These blades 17 and 19 are also radial at their fan peripheries but are quite thin so that the secondary air propelled into the combustion chamber by these two fans enters the chamber as continuous flat ring-like layers of air, one layer immediately above and the other layer immediately below the jets.

The primary air admitted to the middle fan 15 and the secondary air admitted to the upper fan 14 flows from atmosphere through the opening 29 into the interior of casting 30 as shown in Fig. 5. The secondary air supplied to the lower fan 16 is admitted from atmosphere into the conduit 31 in the center post of the combustion chamber. The opening through the center post is constructed with means for water cooling as are also the cast steel parts of the castings exposed to high heat surrounding the driving shaft of the burner. The waste black liquor is admitted through regulating valve 26 into the pipe 25 leading it to the casting 28 where it is fed to the intake of the middle fan 15 of the burner through the cylindrical opening of casting 28 shown in Fig. 5. The valve 27 is a valve for admitting fuel oil for starting up the furnace when it is cold.

A cylindrical checker wall 11 made of chrome blocks with open checker work construction is positioned inside of the cylindrical refractory side wall 7 of the combustion chamber with a clearance space 1a of about one inch between the checker wall 11 and the refractory side wall 7 of the combustion chamber. This wall 11 is built of chrome blocks 12 placed so as to have spaces 13 between each of the chrome blocks so as to have a wall of checker brick construction, shown clearly in Fig. 3.

The function of the space 1a between the cylindrical wall 7 and the checker wall 11 is for the protection of the molten soda, as it flows through the space, from the heat of the furnace and also from the turbulence of the gases within the combustion chamber. A very high percentage of the soda recovered is collected at the point where, immediately after combustion, some of the products of combustion carrying atomized molten soda are thrown against the wall 11, where the atomized molten soda coalesces and wets the surface of wall 11. The molten soda accompanied by a small amount of the hot gases passes through the openings in the wall 11 and enters the relatively quiescent space 1a above referred to.

The floor of the combustion chamber is lined with refractory material, that is chrome brick, and the floor slopes toward the soda collecting conduit 20 positioned at the far end of the flue connecting the combustion chamber with the

separation chamber and shown in Figs. 1 and 2. In the floor of the combustion chamber are a number of troughs 23 covered partially with chrome bricks, on the top of which is a covering of broken chrome blocks 22 extending over the entire floor. In these troughs 23 the molten soda flowing in the space between cylindrical wall 11 and the cylindrical refractory side wall 7 is collected and led to the conduit 20 as shown in Figs. 1, 2 and 4. The molten soda that trickles through the broken chrome blocks 22 in the floor of the combustion chamber also finds its way into troughs 23. Troughs 23 also form a quiescent space within the furnace. It will be noticed that the soda in all these troughs 23 is protected from the direct action of the gases within the furnace. The broken chrome layer 22 in the bottom of the furnace also functions for the collection of the soda and after it has trickled through this broken chrome, it is obvious that it also is protected from the direct heat of the furnace and the rapidly moving gases within the furnace.

The separation chamber 9 forms an extension of the flue 8 and consists of four walls, a top, two side and bottom walls, with an open inlet and outlet. Transverse thereto are rectangular vertical chrome brick walls 32 of checker work construction arranged in pairs with broken chrome blocks 33 between the walls of each pair. The floor of the separation chamber is similar in construction to the floor of the combustion chamber. It slopes toward the soda collecting conduit 20 and contains a number of troughs 23 leading into conduit 20 shown in Figs. 1 and 2. Fig. 10 shows the open checker work construction of walls 32. The hot products of combustion containing some of the molten soda in an atomized state flow from the combustion chamber 6 through the open spaces 32a of the checker work construction of wall 32 of the separation chamber 9 where the atomized molten particles, still carried by the hot products of combustion, coalesce in the broken chrome blocks 33 and flow by gravity into the troughs 23 in the floor of the separation chamber. In this separation chamber the last remaining soda particles are collected and the hot products of combustion leave the separation chamber 9 and enter the boiler.

All the molten soda collected in the conduit 20 from the combustion chamber and separation chamber of the furnace finally flows out of the furnace through the discharge nozzle 21 as shown in Fig. 2.

The heat value of black liquor depends upon the degree of concentration and various other factors. When evaporated to complete dryness, the resulting solid mass will contain an average of about 6500 B. t. u. per pound and the furnace temperatures attainable depend upon the degree to which the concentration is carried out. From actual furnace operation, I have obtained the following results with liquor of the following concentration:

	Degrees F.	65
37° Bé. at 60° F.	2450	
35° Bé. at 60° F.	2200	
33° Bé. at 60° F.	2020	
32° Bé. at 60° F.	1910	70

The 37° liquor contained 60% solids and 40% water, while the 32° liquor contained 50% solids and 50% water and about 3250 B. t. u. per pound.

The problem, however, is not one of simple combustion, but is complicated by the soda re- 75

covery which is directly affected by the temperature of the furnace. The higher the temperature of the furnace, the greater is the loss of soda by volatilization, and also the destructive action of the molten soda on the refractory material of the furnace increases with the temperature of the furnace. Sodium carbonate melts at 1650° F., but for smooth and continuous operation, I prefer to control the furnace to maintain a temperature of about 2000° F. which can easily be obtained with liquor concentrated to 33° Bé. at 60° F. and when operating under these conditions, I have obtained a soda recovery of 93.6%.

I have found that the control of the furnace atmosphere is extremely important and with a furnace of my invention, it can be maintained at any desired condition, within certain ranges. For example, the furnace was operated for long periods with a neutral atmosphere, that is, the analysis of the gases leaving the furnace showed neither free oxygen nor carbon monoxide. The furnace was also operated over a long period with a reducing atmosphere in which the carbon monoxide was maintained at from 2 to 3% and no oxygen, as shown by actual analysis of the gases leaving the furnace. This ability to maintain a definite reducing atmosphere is very important in the sulphate process for a high percentage of soda recovery; as in this process, the soda is recovered in the form of sodium sulphide instead of sodium carbonate recovered in the soda process and the maintenance of a slightly reducing atmosphere is decidedly advantageous.

I have also found that excellent results are obtained with this furnace when the furnace is operated under a pressure of preferably 9 or more inches of water above atmosphere. The benefits of maintaining the pressure in the furnace are manifested with as little as 2 inches of water pressure and become more pronounced as the pressure is increased. This pressure in the furnace is obtained by forcing the products of combustion through a checker wall of refractory brick and also a column of broken brick, preferably a refractory brick known as chrome brick. The entire brick work of the furnace is encased in an airtight steel casing. By maintaining a pressure above atmosphere within the furnace, the gases pass through the furnace with great uniformity and the tendency of the gases to carry fine particles of soda with them is greatly minimized. A pressure above atmosphere within the furnace is also highly beneficial in keeping the soda trough through which the molten soda runs from the furnace at a temperature well above the temperature required to keep the soda in a molten condition. This is due to the fact that a small amount of highly heated products of combustion is forced through the trough or channel through which the molten soda flows.

I prefer to deliver the black liquor to the atomizing burner at a temperature not less than 150° F. and preferably from 200° to 212° F., as at the latter temperature the water in the finely atomized liquor as sprayed into the highly heated furnace flashes into steam almost instantly and thereby prepares the combustible material for practical instantaneous and complete combustion. The flashing of the water contained in these fine particles into steam with almost explosive effect still further intensifies the atomization of the fuel particles and thereby intensifies combustion. By observation I have found that practically all the water has been removed from the combustible particles by the time they

are a very short distance away from the atomizing zone of the burner.

I have found that smooth and continuous operation of the furnace can be secured by maintaining a temperature in the furnace of about 2000° F. and that the black liquor need only be concentrated to about 33° Bé. at 60° F. In this condition the black liquor contains about 55% solid matter and 45% water. This black liquor at a temperature of about 200° F. is pumped into the supply pipe 25, its quantity being regulated by valve 26. Pipe 25 admits the black liquor to casting 28 from which it flows in the form of a thin cylindrical ring-like stream into the inlet of the middle fan 15 of the fuel burner 2. Primary air is also admitted from the space within the casting 30 to the inlet of the middle fan. When this fan is rotated at high speed the primary air atomizes the black liquor fuel at the inlet to the middle fan and the mixture is propelled from the middle fan 15 in the form of a plurality of ribbon-like jets into the combustion chamber. At the same time secondary air from within the casting 30 is admitted to the inlet of the upper fan 14 and secondary air from the conduit 31 is admitted to the inlet of the lower fan 16. As the fan blades of the upper and lower fans are quite thin, the secondary air enters the combustion chamber in the form of flat ring-like layers of air, one layer immediately above and one layer immediately below the fuel and primary air jets. As all three fans have blades of the same diameter at their discharge and as the blades of all fans are radial at exit, the jets of primary air and fuel as well as the adjacent layers of secondary air are all propelled into the combustion chamber at approximately equal velocities and in similar directions. Let us assume that the diameters of all three fans are 18 inches and that the speed of the motor driving these fans is 3600 R. P. M. This gives the fans a peripheral velocity of 282.6 ft. per sec. Let us also assume that the relative radial velocity of the primary and secondary air at exit of the fans is 30 ft. per sec. Then the absolute velocity of the jets and air entering the combustion chamber will be

$$\sqrt{(282.6)^2 + (30)^2} = 284.2 \text{ ft. per sec.}$$

This velocity is considerably greater than the velocity of flame propagation and assures that no burning of the fuel can take place at or near the fuel burner itself. It is only after the jets of fuel and primary air and the adjacent layers of secondary air have decreased in velocity to that of flame propagation, which is in this example approximately 80 ft. per sec., that burning of the fuel can take place. Calculation and observation places this flat ring-like zone of combustion at a diameter of about 9.5 feet for the example in question. In Fig. 1 there is designated a zone of combustion having an inner circular boundary approximately at E and an outer circular boundary approximately at F and in the example above quoted the mean diameter of this free zone of combustion would be approximately 9.5 feet. In order to have complete combustion in a free zone, that is away from the burner and the walls of the combustion chamber, the inner diameter of the cylindrical side wall 11 should be about 13.5 feet, that is, far enough away from the outer boundary of the combustion zone so that there cannot be any flame contact and near enough to this zone so that most of the finely divided particles of in-

combustible molten material present in the fuel have still sufficient velocity to impinge against this side wall 11.

As the fuel burner consists of fans rotating at high speed, a centrifugal pressure is established at the discharge end of these fans. The amount of this pressure can be obtained from the formula:

$$10 \quad \frac{p}{d} = \frac{u_a^2 - v_a^2}{2g}$$

in which

p = pressure rise above inlet pressure in lb. per sq. ft.

15 d = density of air or fuel in lb. per cu. ft.

u_a = velocity at periphery of fan in ft. per sec.

v_a = relative velocity at exit of the fan in ft. per sec.

20 Taking the example previously chosen of 18 inch diameter fuel burner fans operating at a speed of 3600 R. P. M. and assuming that the density of the air supplied to these fans is d equals 0.077 lb. per cu. ft. and the v_a equals 30 ft. per sec.; the pressure rise

$$25 \quad p = \frac{[(282.6)^2 - 30^2] \times 0.077}{2 \times 32.2} = 94.4 \text{ lb. per sq. ft. or}$$

$$30 \quad \frac{94.4}{144} = 0.66 \text{ lb. per sq. in. or}$$

$$0.66 \times 27.7 = 18.3 \text{ in. water.}$$

If the pressure of the fuel and air at inlet of the fans of the burner is atmospheric, then a pressure of 18.3 in. of water above atmosphere is created at the exit ends of the fans due to the centrifugal action of the fans. However, this pressure can only be maintained if the exit area from the separation chamber is made quite small, but pressures from 2 to 9 inches of water can easily be obtained with reasonable exit areas from the separation chamber. Naturally, the larger the exit area, the lower will be the pressure maintained.

The mode of operation is as follows:

45 When starting up the furnace from cold, the furnace is first heated by burning therein fuel oil. For this purpose valve 26 is closed and valve 27 admits fuel oil to the pipe 25. After the furnace has been heated up valve 21 is gradually closed and valve 26, admitting black liquor, is slowly opened. From practical operation it has been found that it will take about a 3-hour period of heating up before the fuel oil valve 27 is entirely closed and the black liquor valve 26 is open to admit the proper quantity of black liquor so that the furnace could operate from then on with the black liquor as the only fuel supplied.

50 As the black liquor fuel enters the combustion chamber at a temperature of about 200° F. and as the relatively large amount of water in this fuel is immediately subjected to radiant heat from the zone of combustion, it almost immediately flashes into super-heated steam so that by the time the fuel jets reach the zone of combustion the fuel has been largely dehydrated. The products of combustion upon leaving the zone of combustion are carried in a downward spiral vortex motion into the flue 8 and this motion of the products of combustion is quite effective in collecting some of the molten incombustible particles of the fuel that have lost their velocity so that they do not carry over to wall 11, and uniting them into droplets having sufficient weight to be precipitated from the moving gases.

75 There are therefore three main means for col-

lecting the molten incombustible material of the fuel. The larger part of the molten incombustible particles are sprayed, by the centrifugal force given to them by the fans, against the wall 11 where they coalesce and commingle with other particles so that they finally flow down the wetted wall 11 or pass through the open checker work of this wall into the rather quiescent space between cylindrical side wall 11 and the inner wall 7 of the furnace. The molten particles thus pass from a turbulent zone to a non-turbulent zone. The fine particles that are carried by the products of combustion downward are either precipitated as rain as above described and pass through the broken chrome blocks covering the floor of the combustion chamber and enter the collecting troughs in the floor of this chamber or enter flue 8 with the products of combustion and are made to flow through the separation chamber 9. In this chamber the broken chrome blocks forming walls 33 permit the final separation of the molten soda from the combustion gases. All this molten incombustible material (the soda compounds in the case of black liquor) ultimately find their way into the troughs in the floors of the combustion chamber and separation chamber, from where they flow into the collecting conduit 20 and out of the furnace through the nozzle 21.

It has also been found advantageous to keep as near a constant furnace temperature of 2000° F. as possible. A lower temperature approaches too closely the melting point of sodium carbonate, which is 1650° F. A higher temperature than 2000° F. would bring about a loss of soda by volatilization. Should the temperature of combustion go above 2000° F. for any reason, a small addition of secondary air would quickly re-establish the desired temperature in the furnace. Increasing the amount of secondary air can be accomplished among other ways by introducing air to the fuel burner fans under a small inlet pressure, thereby increasing the flow of secondary air into the combustion chamber.

It has been found advantageous to have a pressure above atmosphere existing in the combustion chamber and separation chamber. Allowing the products of combustion to flow through the furnace under the influence of an ordinary draft does not insure the products of combustion flowing uniformly through the separation chamber, that is, the products of combustion would find their path of least resistance. However, if the combustion chamber is under a pressure above atmosphere, the products of combustion would be forced to go through all the openings provided in the separation chamber. Creating a pressure in the combustion chamber above atmosphere also forces a part of the hot products of combustion to accompany the molten soda compounds flowing in the various troughs and therefore insures the soda compounds being kept in a molten condition until they are free of the furnace.

The treatment of black liquor has been particularly described. The invention is also applicable to other purposes, as the burning of powdered coal and in the smelting of certain kinds of ores.

It will have been noted that the combustion zone of the burner is placed relatively near to the arched top wall of the furnace. It is distant from the vertical cylindrical wall 7 so as to enable all combustible particles to be efficiently and entirely consumed without impingement upon the walls. Nevertheless, the walls are sufficiently

near to the combustion zone E—F, to enable the incombustible particles as liquids, to remain in a molten state at the time they impinge upon the walls. The wall 11 acts as a baffle or barrier 5 against the turbulent interior of the combustion chamber, and provides a quiescent or non-turbulent zone or space at the other side thereof. It also acts as a coalescing gatherer. Thereafter the troughs for the liquid are protected from 10 intense heat yet kept sufficiently heated to maintain the fluidity of the liquid to its discharge nozzle 21. The liquid is collected by gravity action.

There is a combination between the burner and 15 the specific position of the baffle wall in respect thereto.

The separation chamber acts as a curtained conduit to commingle the liquid particles suspended by flotation in the products of combustion 20 and to collect the same.

The separation chamber is shown in the drawings as having four curtains of refractory bricks of checker work construction arranged in pairs with broken blocks of refractory material 25 between each pair of walls or curtains. It has been found that this separation chamber in some cases need only contain one curtain or wall of checker work construction and that this wall alone is sufficient for the collecting of the molten 30 incombustible material existent in the hot gases entering the separation chamber. Hence, the proper choice of the number of curtain walls necessary in the separation chamber depends upon the kind and the amount of incombustible 35 molten material entering the separation chamber.

The method described herein is not claimed in this application but reserved for an application about to be filed.

While I have illustrated and described the 40 preferred form of construction for carrying my invention into effect, this is capable of variation and modification without departing from the spirit of the invention. I, therefore, do not wish to be limited to the precise details of construction set forth, but desire to avail myself of such 45 variations, modifications, and anticipations as come within the scope of the appended claims.

I claim as new:

1. A furnace for burning fuel consisting of 45 combustible and incombustible materials, comprising a combustion chamber formed of an enclosing closed furnace wall for the combustion of the combustible materials of the fuel producing products of combustion in turbulent movement and for the liquefying of incombustible materials of the fuel, a reticulated wall spaced inwardly from the furnace wall for having impinged thereon the incombustible materials of the fuel in liquid state, said reticulated spaced 50 wall permitting the passage of the liquid incombustible materials therethrough, and forming with the furnace wall a space separated by the reticulated wall from the turbulence of the contents in the combustion chamber enabling the quiescence in the space to separate said liquid incombustible materials from attendant gaseous carriers, a burner within said combustion chamber disposed in respect to said reticulated wall, so that the combustible materials are converted 55 to said products of combustion before said materials reach the said wall, and so that the liquid incombustible products are impinged upon said reticulated wall, and a flue for the products of combustion, forming the only opening in the 60 otherwise closed wall of the combustion chamber.

2. A furnace for burning fuel consisting of combustible and incombustible materials, comprising a combustion chamber formed of an enclosing wall for the combustion of the combustible materials of the fuel producing products of combustion in turbulent movement and for the liquefying of incombustible materials of the fuel, a reticulated wall spaced from the furnace wall for having impinged thereon the incombustible materials of the fuel in liquid state, 5 said spaced wall permitting the passage of the liquid incombustible materials therethrough, and forming with the furnace wall a space separated by the reticulated wall from the turbulence of the contents in the combustion chamber enabling the quiescence in the space to separate said liquid incombustible materials from attendant gaseous carriers, said reticulated wall being formed of suitable refractory bricks and spaces therebetween to enable the liquid materials to 10 coalesce and gather on the surfaces of the bricks and flow through the spaces between the bricks into the non-turbulent, quiescent space between the bricks and the furnace wall, a burner within said combustion chamber disposed in respect to 15 said reticulated wall, so that the combustible materials are converted to said products of combustion before said materials reach the said wall, and so that the liquid incombustible products are impinged upon said reticulated wall, and a flue for the products of combustion, forming the only opening in the otherwise closed wall of the 20 combustion chamber.

3. A furnace for burning fuel consisting of combustible and incombustible materials, comprising a combustion chamber formed of an enclosing wall for the combustion of the combustible materials of the fuel producing products of combustion in turbulent movement and for the liquefying of incombustible materials of the fuel, a reticulated wall spaced from the furnace wall for having impinged thereon the incombustible materials of the fuel in liquid state, said spaced wall forming with the furnace wall a non-turbulent, quiescent space for the passage 35 of the liquid incombustible materials, and a bottom for said combustion chamber, having troughs in communication with the space between said walls, for gathering the liquid incombustibles.

4. A furnace for burning fuel consisting of combustible and incombustible materials, comprising a combustion chamber formed of an enclosing wall for the combustion of the combustible materials of the fuel producing products of combustion in turbulent movement and for the melting of the incombustible materials of the fuel, a reticulated wall spaced from the furnace wall for having impinged thereon the incombustible materials of the fuel in molten state, said spaced wall forming with the furnace wall a non-turbulent, quiescent space for the passage 50 of the molten incombustible materials, and an inclined bottom for said combustion chamber, having troughs in communication with the space between said walls, for gathering the molten 55 incombustibles.

5. A furnace for burning fuel consisting of combustible and incombustible materials, comprising a combustion chamber formed of an enclosing wall for the combustion of the combustible materials of the fuel producing products of combustion in turbulent movement and for the melting of the incombustible materials of the fuel, a reticulated wall spaced from the furnace wall for having impinged thereon the 60

5 incombustible materials of the fuel in molten state, said spaced wall forming with the furnace wall a non-turbulent, quiescent space for the passage of the molten incombustible materials, an
 10 inclined bottom for said combustion chamber having troughs in communication with the space between said walls, for gathering the molten incombustibles, and a layer of suitable broken refractory blocks upon said bottom over said
 15 troughs, said troughs having openings for the entrance of molten incombustible materials.

6. A furnace for burning fuel consisting of combustible and incombustible materials, comprising a combustion chamber formed of an enclosing wall for the combustion of the combustible materials of the fuel producing products of combustion in turbulent movement and for the melting of the incombustible materials of the fuel, a reticulated wall spaced from the furnace wall for having impinged thereon the incombustible materials of the fuel in molten state, said spaced wall forming with the furnace wall a non-turbulent, quiescent space for the passage of the molten incombustible materials, a bottom for said combustion chamber having troughs in communication with the space between said walls, for gathering the molten incombustibles, and a separation chamber formed by an extension of the combustion chamber, and having a transverse curtain wall of spaced refractory bricks.

7. A furnace for burning fuel consisting of combustible and incombustible materials, comprising a combustion chamber formed of an enclosing wall for the combustion of the combustible materials of the fuel producing products of combustion in turbulent movement and for the melting of the incombustible materials of the fuel, a reticulated wall spaced from the furnace wall for having impinged thereon the incombustible materials of the fuel in molten state, said spaced wall forming with the furnace wall a non-turbulent, quiescent space for the passage of the molten incombustible materials, a bottom for said combustion chamber having troughs in communication with the space between said walls for gathering the molten incombustibles, a separation chamber formed by an extension of the combustion chamber, having a transverse curtain wall of spaced refractory bricks, and a layer of broken refractory blocks adjacent to the bricks at one side thereof.

8. A furnace for burning fuel consisting of combustible and incombustible materials, comprising a combustion chamber formed of an enclosing wall for the combustion of the combustible materials of the fuel producing products of combustion in turbulent movement and for the liquefying of the incombustible materials of the fuel, a reticulated wall spaced from the furnace wall for having impinged thereon the incombustible materials of the fuel in liquid state, said spaced wall forming with the furnace wall a non-turbulent, quiescent space for the passage of the liquid incombustible materials, a bottom for said combustion chamber having troughs in communication with the space between said walls, for gathering the liquid incombustibles, a separation chamber formed by an extension of the combustion chamber, having a transverse wall of spaced refractory bricks, a transverse layer of broken refractory blocks adjacent to the said brick wall, and another transverse wall of spaced refractory bricks adjacent to the broken refractory blocks.

9. A furnace for burning fuel consisting of combustible and incombustible materials, comprising a combustion chamber formed of an enclosing wall for the combustion of the combustible materials of the fuel producing products of combustion in turbulent movement and for the liquefying of the incombustible materials of the fuel, a reticulated wall spaced from the furnace wall for having impinged thereon the incombustible materials of the fuel in liquid state, said spaced wall forming with the furnace wall a non-turbulent, quiescent space for the passage of the liquid incombustible materials, a bottom for said combustion chamber having troughs in communication with the space between said walls, for gathering the liquid incombustibles, and a separation chamber formed of top, side and bottom walls and in communication with the combustion chamber, a plurality of pairs of transverse walls of spaced refractory bricks and a layer of broken refractory blocks between the walls of each pair.

10. A furnace for burning fuel consisting of combustible and incombustible materials, comprising a combustion chamber formed of an enclosing wall for the combustion of the combustible materials of the fuel producing products of combustion in turbulent movement and for the melting of the incombustible materials of the fuel, a reticulated wall spaced from the furnace wall for having impinged thereon the incombustible materials of the fuel in molten state, said spaced wall forming with the furnace wall a non-turbulent, quiescent space for the passage of the molten incombustible materials, a bottom for said combustion chamber having troughs in communication with the space between said walls, for gathering the molten incombustibles, a separation chamber formed by an extension of the combustion chamber, and having a transverse curtain wall of spaced refractory bricks, and a bottom for said separation chamber having troughs for molten incombustible materials.

11. A furnace for burning fuel consisting of combustible and incombustible materials, comprising a combustion chamber formed of an enclosing wall for the combustion of the combustible materials of the fuel producing products of combustion in turbulent movement and for the liquefying of the incombustible materials of the fuel, a reticulated wall spaced from the furnace wall for having impinged thereon the incombustible materials of the fuel in liquid state, said spaced wall forming with the furnace wall a non-turbulent, quiescent space for the passage of the liquid incombustible materials, a bottom for said combustion chamber having troughs in communication with the space between said walls, for gathering the liquid incombustibles, a separation chamber formed of top, side and bottom walls and in communication with the combustion chamber, a plurality of pairs of transverse walls of spaced refractory bricks, and a layer of broken refractory blocks between the walls of each pair, and a bottom for said separation chamber having troughs for liquid incombustible materials.

12. A furnace for burning fuel consisting of combustible and incombustible materials, comprising a combustion chamber formed of an enclosing wall for the combustion of the combustible materials of the fuel producing products of combustion in a turbulent movement and for the melting of the incombustible materials of the fuel, a reticulated wall spaced from the fur-

- nace wall for having impinged thereon the incombustible materials of the fuel in molten state, said spaced wall forming with the furnace wall a non-turbulent, quiescent space for the passage 5 of the molten incombustible materials, a bottom for said combustion chamber having troughs in communication with the space between said walls, for gathering the molten incombustibles, a separation chamber formed of top, side and 10 bottom walls and in communication with the combustion chamber, a plurality of pairs of transverse walls of spaced refractory bricks, and a layer of broken refractory blocks between the walls of each pair, and a bottom for said separation chamber having troughs for molten incombustible materials, said troughs being inclined and terminating in proximity to the terminations of the ends of the troughs of the combustion chamber. 15
- 20 13. A furnace for burning fuel consisting of combustible and incombustible materials, comprising a combustion chamber formed of an enclosing wall for the combustion of the combustible materials of the fuel producing products 25 of combustion in a turbulent movement and for the liquefying of the incombustible materials of the fuel, a reticulated wall spaced from the furnace wall for having impinged thereon the incombustible materials of the fuel in liquid state, said spaced wall forming with the furnace wall a non-turbulent, quiescent space for the passage 30 of the liquid incombustible materials, a bottom for said combustion chamber having troughs in communication with the space between said walls, for gathering the liquid incombustibles, a separation chamber formed of top, side and bottom walls in communication with the combustion chamber, a plurality of pairs of transverse walls of spaced refractory bricks, and a layer of broken 35 refractory blocks between the walls of each pair, a bottom for said separation chamber having troughs for liquid incombustible materials, said troughs being inclined and terminating in proximity to the terminations of the ends of the 40 troughs of the combustion chamber, and a common conduit for the troughs of the combustion chamber and separation chamber, said common conduit terminating at the exterior of the furnace. 45
- 50 14. In a furnace for burning fuel consisting of combustible and incombustible materials, the combination of a combustion chamber having spaced walls, an outer closed wall, and an inner reticulated wall, both forming a non-turbulent, 55 quiescent space therebetween, with a burner centrally disposed in said combustion chamber and in line with certain of the reticulations in the reticulated wall, having its combustion zone spaced away from said walls to enable the combustible materials to be converted to products of combustion without the combustible materials impinging upon said walls, and spaced sufficiently near said walls to cause the incombustible materials while still in molten state to impinge 60 upon the surfaces of the inner wall, and in molten state flow into the space between the outer and inner walls. 65
15. In a furnace for burning fuel consisting of combustible and incombustible materials, the 70 combination of a combustion chamber having spaced walls, an outer wall, and an inner wall, both forming a non-turbulent, quiescent space therebetween, with a burner having its combustion zone spaced away from said walls to enable the combustion materials to be converted 75 to products of combustion without the combustible materials impinging upon said walls, and spaced sufficiently near said walls to cause the incombustible materials while still in molten state to impinge upon the surfaces of the inner wall and in molten state flow into the space between the outer and inner walls, said burner being centrally disposed in said combustion chamber and consisting of three rotating fans, the central for the fuel and air, and the upper and lower for air, whereby the fuel is discharged at velocities greater than flame propagation, to a predetermined point where combustion takes place, the radiated heat from the combustion zone changing any water constituents in the fuel to superheated steam while the fuel is traversing the space between the fans and the combustion zone. 80
16. In a furnace for burning fuel consisting of combustible and incombustible materials, and in which the combustible material becomes products of combustion and the incombustible material is reduced to a molten state, a combustion chamber, a fuel burner in said combustion chamber for propelling centrifugally fuel and a sufficient 85 quantity of air necessary for complete combustion in said combustion chamber at velocities sufficiently great to establish a free combustion zone at a predetermined distance from the said burner and from the walls of the combustion chamber, the combustion chamber also having a cylindrical wall of refractory checker brick construction within the walls of the combustion chamber and spaced at a small distance from it forming a quiescent zone between said walls, and 90 a separation chamber having a plurality of walls of refractory checker brick construction with broken refractory brick between each pair of walls through which the hot products of combustion pass in flowing from the combustion chamber, a flue connecting the combustion chamber and separation chamber, the floors of the combustion chamber, separation chamber and flue being covered with refractory brick and broken refractory blocks and contain suitable 95 troughs in which the molten incombustible material flows, a common discharge nozzle for receiving said molten material, and means for rotating the fuel burner at a speed sufficient to maintain a positive pressure within the furnace. 100
17. In a furnace for burning black liquor consisting chiefly of combustible wood products and of incombustible water and soda compounds, a combustion chamber, a fuel burner in said combustion chamber for centrifugally propelling the black liquor and a sufficient quantity of air necessary for complete combustion in said combustion chamber at velocities sufficiently great to establish a free combustion zone at a pre-determined distance from said burner and from any 105 part of said combustion chamber, the distance between the fuel burner and the zone of combustion being sufficient to permit the radiant heat of the zone of combustion to vaporize the water constituent in the black liquor before it reaches the said zone of combustion, a wall of chrome checker brick construction within the walls of said combustion chamber and spaced a small 110 distance from it to form a quiescent zone between the two walls and near enough to the zone of combustion to permit molten particles of the soda compounds to impinge upon the said checker brick wall and to enter the said quiescent zone, a separation chamber having transverse walls of chrome checker brick construction, a flue 115

connecting the combustion chamber and separation chamber, the floors of the combustion chamber, separation chamber and flue being covered with chrome brick and broken chrome blocks and contain suitable troughs for collecting the molten soda compounds and discharging these soda compounds from a common discharge nozzle, and means for rotating the fuel burner at a speed sufficient to maintain a pressure above atmosphere within the furnace.

18. In a furnace for burning black liquor consisting chiefly of combustible wood products and incombustible soda compounds and water, the combination of a combustion chamber, a burner therein centrally located in the upper portion thereof, a separation chamber having restricted openings for the passage of fluid therethrough, a flue connecting said combustion chamber with said separation chamber, and means maintaining a pressure above atmospheric during the operation of the burner, throughout the combustion chamber, the flue, and the flue end of the separation chamber, whereby the burning of said black liquor by separating its combustible wood products from the incombustible soda compounds and water takes place in a pressure above atmospheric.

19. In a furnace for burning black liquor consisting chiefly of combustible wood products and incombustible soda compounds and water, the combination of a combustion chamber having a wall of chrome checker brick construction near the wall of the combustion chamber and forming a quiescent space between the two walls, a fuel burner for centrifugally propelling the black

liquor and air necessary for combustion in the combustion chamber under a pressure above atmospheric and at a velocity greater than that of flame propagation, whereby a free zone of combustion is formed a sufficient distance away from the burner to permit the radiant heat of the zone of combustion to dehydrate the black liquor before it reaches the zone of combustion, yet close enough to the chrome checker brick wall to permit the molten finely atomized incombustible soda compounds as they leave the zone of combustion to impinge on said walls, coalesce and enter the said quiescent space beyond the chrome checker wall, a separation chamber having transverse walls of chrome checker brick construction through which the products of combustion and superheated steam flow, a flue connecting said combustion chamber with said separation chamber, the floors of the combustion chamber, flue and separation chamber being covered with chrome bricks and containing troughs for collecting the molten soda compounds and carrying them to a common discharge while the soda compounds are still in a molten state.

20. In a furnace, a separation chamber having a plurality of transverse walls of checker refractory brick construction arranged in pairs with broken refractory blocks between each pair of walls, said separation chamber having troughs for collecting molten incombustible material entrained by the walls when products of combustion carrying molten material pass through the open spaces of the checker brick walls and broken blocks.

JOHN E. GREENAWALT. 35
